MARTIN LANDENBERGER, JR., OF PHILADELPHIA, PENNSYLVANIA,
ASSIGNOR TO THE E. H. GODSHALK COMPANY, OF SAME PLACE.

DESIGN FOR A FABRIC.

Design No. 17,648, dated August 23, 1867.

UNITED STATES PATENT OFFICE.

MARTIN LANDENBERGER, JR., OF PHILADELPHIA, PENNSYLVANIA,
ASSIGNOR TO THE E. H. GODSHALK COMPANY, OF SAME PLACE.

DESIGN FOR A FABRIC.

SPECIFICATION forming part of Design No. 17,648, dated August 23, 1887.

Application filed May 2, 1887. Serial No. 236,885. Term of patent 3½ years.

To all whom it may concern:

Be it known that I, MARTIN LANDENBERGER, Jr., a citizen of the United States, residing in the city and county of Philadelphia, State of Pennsylvania, have invented and produced a new and original Design for a Fabric, of which the following is a specification, reference being had to the accompanying photograph, forming part thereof.

10 The leading features of my design for fabric are stripes having fluffy faces alternating with set-back stripes having plain faces.

Referring to the photograph, A represents a piece of fabric having stripes ab. The stripes a are fluffy and alternate with the stripes b, 15 which are comparatively plain, the stripes a b being of different widths. The stripes a are in relief, while the stripes b are set back or depressed.

I claim—

20 The design for a fabric herein described and shown, comprising the striped fluffy surface of uniform height, separated into parallel bars by means of the straight lines b.

MARTIN LANDENBERGER, JR.
